FOLDING BOX CONSTRUCTION

Mary Elizabeth Frasch, Columbus, Ohio

Application June 7, 1956, Serial No. 589,961

1 Claim. (Cl. 229—33)

This invention relates to box construction and particularly to that class of folding boxes which are composed of paperboard or the like and are cut from a single blank of board-forming material.

The present invention has for its object to provide a folding box which may be readily set up for use at the time products are to be placed therein, so that prior to such usage, the blanks will be in flat, compactly grouped state, occupying but a minimum of space during shipment and storage.

Another object is to provide a one-piece folding box which, when folded and set up for use, provides an outer frame composed of multiple thickness of the board material from which the box is formed, whereby to provide a frame of marked strength, rigidity and load-sustaining characteristics.

A further object is to provide a one-piece box of the character indicated in which the panel forming the top wall of the box terminates at its sides in downwardly folding webs which engage the inner surfaces of the side walls of the box to brace and reinforce the same, the webs, in turn, terminating in inwardly projecting, freely swinging wings which are adapted to engage products loosely placed in the box to hold the same against bunching, displacement or wrinkling when the box is handled.

A still further object of the invention is to simplify and improve the construction and arrangement of the component parts of the box.

With these and other ends in view which will readily appear as the nature of the invention is better understood, the same consists in the improved construction and novel arrangement and combination of parts which will be hereinafter fully described and particularly pointed out in the appended claims.

In the accompanying drawing there has been illustrated a simple and preferred form of the invention, it being, however, understood that no limitation is necessarily made to the precise structural details therein exhibited, but that changes, alterations and modifications within the scope of the claims may be resorted to when desired.

In the drawings:

Fig. 1 is a plan view of the blank from which the folding box of the present invention is formed;

Fig. 2 is a perspective view disclosing the box when folded but with the top and bottom walls of the box separated for the placement of products therein;

Fig. 3 is a vertical longitudinal sectional view taken through the box when closed and disclosing the webs of the top wall in reinforcing engagement with the side walls of the box and with the free-swinging wings carried thereby in holding contact with the box contents;

Fig. 4 is a horizontal sectional view taken through the reinforced front wall construction of the box and disclosing the tying means therefor;

Fig. 5 is a vertical transverse sectional view of the box and taken on the line 5—5 of Fig. 3;

Fig. 6 is a vertical longitudinal sectional view showing

2

a slightly modified form of side wall construction for the box, disclosing an additional reinforcement therefor.

Corresponding parts in the several figures are denoted by like characters of reference.

5 The folding box of the present invention is formed from a single blank B of foldable sheet material, preferably paperboard. This blank is cut and scored to form generally a base section and a closure section each comprising a plurality of integrally joined panels, wherein is 10 embodied a substantially rectangular bottom wall 1, a correspondingly formed and dimensioned top wall 2, and relatively narrow, elongated, side walls 3, a back wall 4 and overlapping front walls 5 and 5a, the front wall 5 being carried by the bottom wall 1 and the other front 15 wall 5a by the top wall 2. At this point I desire to have it understood, that the use of the words in the specification and claims such as "top, bottom, front, back and side" are employed merely for the purpose of facilitating a clear understanding of the form and arrangement of the box parts and not by way of limitation, since the quoted words have been used herein primarily because of the positions of the box parts as illustrated in the drawings, and that if the box should be placed 20 in other positions, such descriptive words are, for purposes of their instant usage, to be considered adequately descriptive.

The bottom wall 1 is foldably joined with the front and back walls 5 and 4 along the score or fold lines 6 and 7, while the side walls 3 are foldably joined with the 30 bottom wall 1 by the score or fold lines 8. The side walls 3 are formed with front wall flaps or extensions 9 and are flexibly joined therewith by the score or fold lines indicated at 10, so that these extensions will fold in overlapping order against the front wall 5 when the box is 35 set up for use. Also, the side walls 3, in alignment with the rear wall 4, are formed with rear wall reinforcing flaps 11 which are free to fold about the score lines 12 to engage the rear wall 4 and reinforce its corner construction with the side walls 3.

40 The top wall 2 at the sides thereof is formed with spaced parallel fold lines 13 and 14, defining between the side wall-reinforcing webs 15. Beyond the score lines the top wall is extended to provide merchandise holding and position-maintaining wings 16.

45 In folding the blank to form the set up, merchandise-receiving box, the side walls 3 are folded about the score lines 8 to assume an upright position with respect to the horizontally positioned bottom wall. The side wall flaps 11 are folded inwardly about the score lines 12 and, 50 likewise, the side wall extensions 9 are correspondingly folded about score lines 10. The rear wall 4 and front wall 5 are correspondingly folded about their score lines 7 and 6, respectively, to upright positions, as shown in Fig. 2. The top wall 2 is then inwardly folded about 55 the score line 17, so that it will fold over the bottom wall 1. The webs 15 are correspondingly folded about the score lines 13, the wings 16 about the fold lines 14 and the front wall 5a about the fold line 18, thereby completing the folding of the blank.

60 With the blank so folded the contents 19 of the box are placed therein and the box is rendered secure and fastened by a tying cord or tape 20. The intermediate portion 21 of the cord is positioned on the inner surface of the front wall 5 and the two ends of the cord are then 65 passed through eyes 22 formed in the wall 5 and through registering eyes 23 formed in the front wall 5a of the top wall, through eyes 24 formed in the overlapping side wall extensions 9, the free ends of the cord being then tied and united by a slip knot, thereby holding the box 70 in secure, assembled order.

It will be noted that the box frame, as produced by the walls 3, 4 and 5 and their associated extensions and flaps

9 and 11, provide a rigid reinforced structure composed of multiple thickness of assembled parts. Thus, the rear wall 4 is braced by the flaps 11, particularly in its corner regions with the side walls 3. The side walls 3 in the assembled box are reinforced along their full lengths by the webs 15 and the front wall constructions include the full length walls 5 and 5a and the overlapping extensions 9 of the side walls. Such strong framing is important in enabling the box to carry heavy bulky merchandise, such, for example, as a heavy top coat. When the box is so heavily filled, the wings 16 contact the top wall 2 and reinforce and brace it with double thicknesses of the paperboard material. When the box is lightly loaded, as when it receives lightweight, silky garments which do not take up the full volume of the merchandise-receiving space of the box, the wings 16 fold or swing downwardly, away from the top 2 and into contact with such light-weight contents, holding the latter secure against displacement and their tendency to bunch and wrinkle when loosely placed in boxes of prior usage.

In the modified form of Fig. 6, the side walls 3 are extended laterally of the blank B, as it is viewed in Fig. 1, to provide reinforcing flaps 25 which are confined between the top-carried webs 15 and said side walls, thereby reinforcing the side wall areas of the box frame with an additional thickness of paperboard in enhancing its mechanical strength.

I claim:

A foldable paperboard box of integral one piece construction comprising a base section composed of a flat rectangular bottom wall, opposed side walls, a front wall and a back wall, said side, front and back walls being foldably connected along fold lines with said bottom wall and extending upwardly in perpendicular relation thereto, said side walls being formed at each end thereof with hingedly connected front and rear extension flaps folded inwardly in overlying relation to the front and back walls

respectively of said base section, the front extension flaps of said side walls being of a length to completely overlap the front wall of said base section and to partially overlap one another; a closure section composed of a flat, rectangular top wall of substantially the same area as said bottom wall foldably carried by the back wall of said base section for free hinging movement with respect thereto, opposed, downturned side-forming webs hingedly joined with the side edges of said top wall and terminating in a pair of relatively elongated downwardly extending article-engaging wings, and a downturned, front wall flap hingedly connected with the edge of said top wall opposite the back wall of said base section, said closure section being arranged upon closure of the box to telescope within said base section with the side-forming webs of said closure section lying adjacent to and enclosed by the side walls of said base section and with the front wall flap of said closure section telescoped between the front wall and the front extension flaps of the side walls of said base section, the front flap of said closure section and the front wall and front extension flaps of said base section being formed with relatively registerable openings for the reception of a flexible tie; and a flexible tie member extending through said openings and securing said closure section in closed relation to said base section.
